UNITED STATES PATENT OFFICE.

ANDREW HAUCK, OF BROOKLYN, NEW YORK, ASSIGNOR TO WILLIAMSBURGH WOOD HEEL COMPANY, OF BROOKLYN, NEW YORK, A CORPORATION OF NEW YORK.

MANUFACTURE OF WOODEN HEELS.

Application filed July 25, 1925. Serial No. 46,071.

This invention relates to the operation of turning wooden heels. As heretofore practiced, the turning operation involves the clamping of the heel block in a "jack" and shifting the jack to carry the heel block first into engagement with one cutter and then reversely to carry the opposite side of the block into engagement with a second cutter. These two-spindle machines as they are called, have become the standard in the manufacture of wood heels and this despite the fact that it is difficult and practically impossible to set two spindles and two sets of cutter blades so that they will cut the opposite sides of a heel block exactly alike and merge the cuts smoothly at the back of the heel.

One of the primary objects of this invention is to accomplish the turning of wooden heels completely in a single spindle machine and with one and the same set of cutters.

Other objects of the invention are to turn wooden heels with a continuously smooth exterior and without the usual ridge such as is left at the back of the heels turned in the standard two-spindle machine; and in addition to effecting savings in the cost and complication of the machinery to effect economies in the cost and time of operation and enable the use of ordinary labor in place of the highly skilled labor required for the attention and operation of the two spindle machines.

The foregoing and other desirable objects are attained in this invention by certain novel features of construction, combination, relation of parts and special operation, as will be clear from the following specification.

The drawings accompanying and forming part of this specification illustrate a practical embodiment of the invention, wherein:

Figure 1 is a vertical sectional view of a single spindle wood heel turning machine embodying the principles of this invention.

Figure 2 is a broken top plan view of the same.

Figure 3 is a detached plan view of the cutter head.

Figure 4 is a cross sectional view of the holder as on the plane of line 4-4 of Figure 3.

Figures 5, 6, 7 and 8 are somewhat diagrammatic views illustrating successive stages in the turning of the heel.

Figure 9 is a diagrammatic plan illustrating the condition of the cut at the half-way point in the turning of a heel on the standard two-spindle machine.

Figure 10 is a view of the heel turned on this machine, showing the ridge left at the back by the joinder of the two cuts.

Figures 11 and 12 respectively are comparative views illustrating the longer, flatter cut, enabling the complete turning on the one spindle in this invention and the smoothly turned heel free of any ridges or breaks in the continuity of surface.

The machine illustrated has a single upright spindle 15 journaled in upper and lower bearings 16, 17 and shown driven by a directly connected electric motor 18. Cooperating with this one spindle is a heel jack 19 shown as having a clamping head 20 riding on an upper track 21 and a post 22 riding on a lower track 23.

The cutter consists in the illustration of a series of three cutter blades 24 secured by bolts 25 to the flanges 26 of the cutter head 27 fixed on the upper end of the spindle. In addition to the extra blade this cutter differs from the regular or standard cutter of the two-spindle machines by operating on an arc A of considerably greater radius R, as illustrated diagrammatically in the comparative Figures 9 and 11. Also in this single spindle machine the tips of the blades are given an outward "hook" substantially to the extent indicated by the broken line 28 in Figure 11 so as to produce more of a "scraping" cut and hence are less liable to "dig into" the wood when working across or against the grain.

The effect of the greater radius is especially important as will be apparent from consideration of Figures 9 and 11. In the standard practice, the diameter of the cutter head is usually approximately four and three-quarter inches. In the new, single spindle machines now in operation, this radius is practically doubled, the cutter heads being about eight inches in diameter. With the shorter radius the arc is smaller and this lesser more acute curve brings the

ends of the grain into successively greater prominence where they present such angles to the cutter blade that any further turning of the block will cause the blades to dig in 5 and split the block or tear it out of the jack.

The greater radius of the cutters in Figure 11 creates a shallower or flatter curved cut in which the successive ends of the grain do not stand out in such relief and 10 so actually offer a greatly diminished resistance to the cutter blade. Also, the longer arc produces a greater length of cut so that with the heel blocks in the same relative positions shown in Figures 9 and 11, 15 the new cutter will have cut clear across the back and taken away part of the far corner of the block while in the standard machine only the back portion of the block will be cut and the entire corner portion 20 will not have been touched. With this relatively flat cut and the more "scraping" angle of the blades, the chips are smaller even though the aggregate result due to the 25 longer cut is greater.

This new three bladed cutter may be rotated at substantially the same speed as the standard two-spindle cutters but in some instances it has been found desirable to operate them at a somewhat higher speed of 30 rotation.

In the first stage of the turning operation, indicated in Figure 5, the block 29 is presented to the cutter, as shown in broken lines, and then rotated to finish from the 35 breast backward along the first side 30. The continuance of this movement carries the cut across the back and takes away the main part of the corner of the block, as at 31 in Figure 6. In the third quarter 40 of the operation indicated in Figure 7, the cutter is operating against the grain but as most of the corner has been removed in the preceding stage, and the blades have a scraping effect, removing but small chips, 45 this portion of the cut is effected without tearing or biting into the grain. From this stage the cutters are working with the grain and finish off the far edge of the heel at 50 32 while so cutting with the grain, leaving a smooth clean finish.

The operation is continuous and uninterrupted and all the operative need do is to feed the work to the cutter and turn it to extend the cut from the first side clear 55 around to the opposite side of the block, the jack and the supporting tracks taking care of the angles necessary to produce the desired contour of cut.

This invention, it will be seen, may eliminate the need for the specially skilled operatives heretofore required in the wood heel turning art because with this new machine it is simply necessary to clamp the block in the jack and then after advancing 60 one side of the block to the cutter, to swing

the jack in just the one direction to carry the cut continuously around to the far side of the block. The saving in time over the old two-spindle method, because of the uninterrupted character of the operation, is 70 considerable. Further, economies in time, labor and final cost, result from the fact that the turned surface of the heel is completely finished in the single turning operation so that no subsequent "sanding" or finishing is required to remove a ridge or other cutter marks such as left by the two-spindle 75 machines.

The ridge left at the joinder of the two side cuts is recognized as a characteristic of heels turned on the standard two-spindle machines and the removal of this ridge in the subsequent sand papering operation usually leaves a flat streak, characterizing the finished product. The new heels are 80 distinguished from both by the absence of either a ridge or a "flat" and so are distinguished by the smooth continuity of the turned surface. This smooth unbroken surface has the additional advantage that the 85 cover which is stretched over the heel will fit smoothly without leaving any ridges or grooves such as usually shown through on the two-spindle heels.

The tracks which guide the jack are shown 90 as constructed as in the patent to W. F. Edson No. 25,326, patented Sept. 6, 1859 so that they may be raised and lowered to act as cams for tilting the jack in various ways to produce different heel shapes. The 100 cutting edges of the blades are given a shape to produce the desired contour and a special feature in this connection is that the greater radius of the cutter head and the inclining of the tail ends of the cutter 105 blades inward toward the center enable the use of longer blades and hence provide for the regrinding of the blades a great number of times. This larger size cutter head 110 also acts with a fly wheel effect, steadyng the running of the machine and preventing vibration.

The form or pattern plate 33 carried by the jack and the gage or guide 34 with which it cooperates are both designed for the complete rotation of the jack about the cutter, that is, to carry the block completely around from one side to the other and in this respect they differ from the patterns and guides of the standard two-spindle 115 machines.

The guide is shown as adjustable by means of a screw 35 and as having a reference scale 36. In different sizes of the same style of heel it is sometimes desirable to vary the proportion between the top and bottom of the heel. The cutter spindle is therefore shown mounted so that it may be tilted about the center 37 which forms a pivotal support for the upper bearing. The 120 125 130

extent of such tilting movement is governed in the illustration by a slotted gage 38 projecting from the lower bearing and secured by clamp screw 39. It will be seen that 5 when the cutter spindle is adjusted to swing the top of the cutter outwardly, the bottom of the heel will be cut proportionately smaller than when the cutter spindle is tilted to carry the top of the cutter inwardly or away 10 from the jack. This adjustment also may be made use of for producing different contours. The extension of the cut completely from the first side around the back and to the end of the opposite side of the heel has 15 the effect not only of shaping but also of actually laying the grain all in the same direction so that the surface is perceptibly smoother and less porous than produced by two-spindle machines with their two independent sets of sequentially operating cutters.

The extension of the cut continuously in one direction is of advantage also in cases where the heel is applied to a sanding machine 25 because the sanding machine rotates in the same direction as the single cutter of this new turning machine and so has the effect of further smoothing and laying the grain of the wood all in the same direction. 30 The sanding operation, however, is not necessary for ordinary purposes with this invention and is only employed where an extra smooth surface is desired.

The use of a single cutter for the complete 35 turning operation enables the employment of simple flat tracks for the jack both at the top and the bottom. This is another great advantage over the two-spindle machines which require the upper and lower 40 tracks to be shaped as "cams" to raise and lower and tilt the jack at different periods in its travel with respect to the two spindles and further require the "filing" of these 45 tracks by hand to give them the initial shape and to keep them in trim as they wear down. The straight edge tracks employed 50 in this machine require no shaping or filing adjustments and as they can be inexpensively produced they may be simply thrown away as they become worn and be replaced 55 by new flat tracks. Furthermore, these flat faced tracks can be made as true arcs of a circle, both top and bottom, having as centers, a point or points approximating the cutting line of the cutter and these flat faced 60 part circular tracks require less time and care in adjustment than the special cam tracks of the two-spindle machines.

It will be clear from the foregoing that 65 various modifications and changes may be resorted to without departure from the true spirit and scope of the invention as hereinafter broadly claimed and it should be understood, furthermore, that the terms employed herein are used in a descriptive

rather than in a limiting sense, except for such limitations as may be imposed by the state of the prior art.

What is claimed is:

1. The process of turning a completely 70 finished wooden heel in a single continuous operation which includes relatively shifting a wooden heel block and a continuously operating cutter with respect to the center of the block with a continuous uninterrupted movement while the block and cutter are engaged to extend the cut continuously from the breast end of one side of the block around the back of the block to the breast end of the opposite side of the 75 block.

2. The process of turning a completely 80 finished wooden heel in a single continuous operation which comprises shifting a wooden heel block with respect to a continuously 85 operating cutter while engaged with the cutter and with a continuous uninterrupted movement to extend the cut continuously from the breast end at one side of the block around the back of the block to the breast 90 end at the opposite side of the block.

3. The process of turning wooden heels which comprises rotating a series of contour cutter blades on a flatter arc than the standard practice in wood heel turning machines to produce a flatter shallower cut with 95 smaller chips and rotating the heel block completely around from one side across the end to the opposite side while in contact with the cutter to thereby turn a complete 100 smoothly continuous surface free of ridges and requiring no secondary finishing treatment.

4. A machine for completely turning 105 wooden heels from the rough wooden blocks in a single continuous and interrupted operation comprising but one upright cutter spindle, a single cutter on the upper end of said spindle and having a plurality of cutter blades forming a cutter head of greater 110 diameter than the cutter heads of standard two spindle wood heel turning machines so as to make a wider and flatter cut than such standard cutters, a jack for holding 115 the heel block and cooperating pattern and guide means for directing said jack in a predeterminedly varying compound arcuate and rotary movement about the spindle from one side to the opposite side of the same and sufficient in extent to carry the 120 block in the jack from a position at one side of the spindle with the first corner of the block presented to the cutter, successively and continuously along the first side and around the end of the block to the opposite 125 side and to the final corner directly opposite the first corner.

5. The process of turning wooden heels which comprises traversing a succession of 130 cutter blades in a flatter arc than the cutter

blades of standard two-spindle wood heel turning machines and relatively rotating a wooden heel block about said cutter from one side, around the back to the opposite side of the block and thereby producing a continuously smooth turned heel contour with the grain laid all in one direction.

6. The process of turning wood heels with a continuously smooth contour which comprises advancing one front corner of the heel block to a rotating cutter and then continuously turning the heel block to extend the cut from the front corner along the first side across the back and along the opposite 10 side to the other front corner of the block.

7. A single spindle wood heel turning machine comprising an upright spindle, a cutter head carried thereby, a series of more than two cutter blades on said head having 20 their cutting edges at a radius greater than the standard two-spindle wood heel turning machine, a jack and guide means for the same extending about the spindle from one side clear to the other side, enabling the 25 shifting of the jack to carry a heel block clamped therein from a position with one side of the block presented to the cutter uninterrupted around to a position with the opposite side of the block presented to the 30 cutter.

8. A wood heel turning machine comprising a single upright spindle, a cutter head carried thereby, cutter blades carried by said head, a heel block jack, substantially 35 semi-circular upper and lower tracks extending about the single cutter spindle and having substantially flat upper faces for guiding the jack in a continuous swinging movement about the cutter from one side to the other side of the same, a form carried by 40 the jack and a guide for said form extending about the front of the spindle from one side to the opposite side of the same to cooperate with the form in the turning of 45 the heel block from the first side clear around to the opposite side of the same.

9. A wood heel turning machine comprising a single upright spindle, a cutter head carried thereby, cutter blades carried 50 by said head, a heel block jack, substantially semi-circular upper and lower tracks extending about the single cutter spindle and having substantially flat upper faces for guiding the jack in a continuous swinging movement about the cutter from one side to the other side of the same and a pivotal mounting for the spindle adjacent the cutter head for enabling tilting adjustments of the cutter with respect to the substantially flat 55 tracks.

10. The process of completely turning a wooden heel in a single operation which comprises providing a cutter operating on a flatter arc than the cutters of standard two-spindle wood heel turning machines, ad- 60

vancing one side of a wooden heel block to engagement with said cutter and then turning said block while so engaged with the cutter to extend the cut continuously from said first side of the block about one end 70 and along the opposite side of the block.

11. The process of completely turning a wooden heel in a single operation which comprises relatively shifting a cutter and a wooden heel block to effect engagement with 75 the cutter cutting against the grain of the wood at one side of the block and then further relatively shifting the block and cutter while so engaged to extend the cut continuously along said first side of the cut 80 about the end of the block and along the opposite side of the block and finishing the cut with the cutter working with the grain of the wood at the end of the turning operation. 85

12. The process of turning wooden heels which comprises advancing the forward end at one side of a wooden heel block to a cutter rotating continuously in one direction and rotating the block thus engaged with the 90 cutter in the same direction as the rotation of the cutter and with one continued movement to extend the cut continuously along said first side of the block, across and about the back of the block and along the opposite 95 side to the front end of said opposite side.

13. The process of turning a finished wooden heel in a single continuous operation which comprises advancing the breast end of one side of a wooden heel block to a cutter 100 rotating in a direction to cut against the grain of the wood and rotating the block thus engaged with the cutter in the direction corresponding to the direction of rotation of the cutter in one continued movement sufficient to extend the cut along said first side of the block, about the end of the block and along the opposite side of the block to the breast end of such opposite side and 110 finishing the cut with the cutter working with the grain of the wood at the end of the turning operation. 110

14. A single spindle wood heel turning machine comprising an upright cutter spindle, a cutter head on said spindle of larger 115 diameter and having a greater number of cutters than the cutter heads of standard two-spindle wood heel turning machines, a jack for holding a wooden heel block, substantially semi-circular upper and lower 120 tracks extending about said cutter spindle to opposite sides of the same and having substantially flat upper edges for guiding the jack about the cutter spindle from one side to the opposite side of the same, a guide 125 extending about the spindle from one side to the other side of the same and a form carried by the jack and riding over said guide from one side of the spindle around to the opposite side of the same. 130

15. In a wood heel turning machine, a cutter spindle mounted for tilting adjustments and provided with means for rotating the same irrespective of such tilting adjustments, a jack for holding a wooden heel block, substantially semi-circular flat tracks extending about said spindle and adapted to carry the jack from one side clear around to the opposite side of the spindle, said tracks adapted to be tilted independently of

the tilting adjustments of the spindle, a form carried by the jack and a guide for said form extending about both sides of the spindle and adjustable independently of both the tilting adjustments of the spindle and the 15 tilting adjustments of the tracks.

In witness whereof, I have hereunto set my hand this 23rd day of July, 1925.

ANDREW HAUCK.
